PNEUMATIC EXPANDER FOR HONING MACHINES

Albert M. Johnson, Rockford, Ill., assignor to Barnes Drill Co., Rockford, Ill., a corporation of Illinois

Application January 22, 1957, Serial No. 635,404

2 Claims. (Cl. 51—34)

This invention relates to honing machines in which one or more abrasive elements or sticks carried by a rotary tool are, after entry of the tool in a rough bore, expanded rapidly into contact with the bore wall and then held against the latter under proper pressure for efficient cutting as the tool is reciprocated back and forth until the bore has been enlarged to the desired size. Thereupon, the elements are collapsed rapidly and withdrawn from the bore.

The primary object of the present invention is to provide an expanding mechanism which is extremely simple and inexpensive in construction, which permits the working faces of the abrasive sticks, although being expanded rapidly, to engage the bore wall under a controllable pressure lighter than has been possible heretofore, and which enables the cutting action of the abrasive to start immediately after such contact.

Another object is to utilize the elastic character of a compressed gaseous medium to achieve the foregoing cycle while cushioning the contact of the abrasive sticks and the bore wall at the end of the rapid expansion without at the same time interfering with rapidity of the collapse at the end of the cycle.

A more detailed object is to expand the hone by a pneumatic actuator to which the flow of compressed air is restricted in a novel manner such as to achieve rapid expansion but contact with the bore wall under a light selectively adjustable pressure.

A further object is to sense the failure of the abrasive surfaces to cut properly due to glazing or other causes and to correct such condition by automatically increasing the expanding pressure.

Another object is to utilize an automatic sizing device to perform the additional function of sensing such cutting failure.

The invention also resides in the novel manner of achieving the desired rapid expansion without interfering with the rapid collapse of the hone.

Other objects and advantages of the invention will become apparent from the following detailed description taken in connection with the accompanying drawings in which

Figure 1 is a schematic view and circuit diagram of a honing machine equipped with an expanding mechanism embodying the novel features of the present invention.

Fig. 2 is a similar fragmentary view showing a modified circuit arrangement.

In the drawing, the invention is shown for purposes of illustration incorporated in an automatic honing machine for entering an expandable honing tool axially 10 into the bore 11 of a workpiece 12 clamped on a suitable fixture and reciprocating the expanded tool back and forth until the bore is enlarged to a desired diameter. The tool is carried on the end of a rotary spindle 14 driven by a motor 15 and journaled in a head 16 which is moved back and forth along guideways 16a by a hydraulic actuator 17 to which pressure fluid from a source 18 is admitted under the control of a relay valve 19.

2

The honing tool shown is of conventional design comprising a body 20 fixed to the lower end of the spindle 14 and having slots angularly spaced around its periphery to receive and guide abrasive elements or sticks 22. The latter are backed by the followers 23 of conical cams 24 spaced along a push rod 25 which extends up through the hollow spindle. When the rod is forced downwardly, the sticks are expanded and held against the bore wall under a pressure corresponding to the magnitude of the force applied to the push rod. As the latter is retracted or drawn upwardly, the abrasive sticks are retracted as by garter springs 26 encircling the ends of the abrading elements, the collapsed hone then being adapted to enter the usual guide ring (not shown). Expansion and collapse of the hone is effected by a fluid pressure actuator comprising a piston 27 coupled to the push rod above the upper end of the spindle and slidably in a cylinder 28 mounted on the reciprocable head 16.

Operation of the valve 19 to define a conventional honing cycle is governed by well known mechanism such as that disclosed in Patent No. 2,381,572. In this control, a disk 31 carrying spaced dogs 32 and 33 is oscillated about its axis through a chain connection 34 with the honing head 16 and has loose thereon an arm 36 engageable by the dogs and carrying a cam 37 which acts on a follower lever 38 fulcrumed at 39. Through connections 40 and 41, the lever is joined to the armature of the solenoid R4 and to the operating arm of the pilot valve 43. The latter directs the flow of pressure fluid from the source 18 to the actuators of the valve 19. The outer end of the arm 36 operates as a cam on a follower 44 to actuate a switch S2. Through the connection 41, the lever 38 also actuates a switch S3.

Enlargement of the bore to the desired size is determined by a suitable gaging device 50 which in the present instance is of the type disclosed in Patent No. 2,777,257. Briefly, this device comprises a plurality of nozzles 51 mounted on a laterally floating carrier 52 on the tool body 20 and adapted to direct jets of fluid such as liquid coolant from a pressure source 53 against the wall 11 as the tool moves back and forth in the bore. The coolant is delivered to the nozzles through a conduit 54, a transfer ring 55 surrounding the spindle, and a passage 56 extending down to a chamber with the nozzle carrier. Branching from the conduit 54 is a conduit 54a terminating in a master orifice 57 which cooperates with the nozzle orifices and restrictions 58 and 59 to form a hydraulic bridge the balance of which is sensed by bellows 60 and 61 whose opposed movable ends are coupled to the arm of a switch 62. The arrangement is such that when the bore being felt of by the fluid jets is undersize, the relatively high backpressure in the passage 56 will hold the switch open. The control pressure decreases progressively as the bore is enlarged and finally, at the desired size determined by the setting of the master orifice 57, the switch 62 will be closed thus giving the up-to-size signal.

In the operation of production honing machines of the above character, it is desirable, after the collapsed hone has entered the rough work bore, to expand the hone rapidly until the active surfaces of the sticks approach or contact the bore wall and then press the sticks against the wall under the required working pressure by continuing the expansion of the sticks. Finally, when the bore is up-to-size, the tool is collapsed rapidly and withdrawn from the bore.

In accordance with the present invention, such rapid expansion followed by slow expansion under increased pressure is effected pneumatically by so controlling the admission of compressed air to the cylinder 28 that the sticks 22 are expanded rapidly against the bore wall but come into contact with the latter under extremely

light pressure after which contact the pressure builds up to the value required for proper and rapid abrading action. More particularly, the invention contemplates admitting air to the cylinder at a supply pressure of sufficient magnitude to provide the final working force but at a rate correlated with the displacement of the piston 27 required to produce contact with the bore wall, such rate being adjusted to so restrict the inflow of the air that there is no substantial build up of pressure in the cylinder until after the sticks have come against the bore wall. Thus, although the sticks may be moved quite rapidly to the bore wall, the pressure of the engagement is so low and so cushioned by the compressibility of the propelling air that there is no danger of damaging the relatively brittle abrasive sticks. This desirable action is achieved without in any way interfering with the rapid collapse of the hone to terminate the cycle with a minimum time delay.

To the foregoing ends, air compressed to the proper regulated pressure, for example 50 p.s.i., is delivered to the expanding actuator from a source 64 through a valve 65 and a suitable pressure regulator 66^a. Herein the latter comprises an orifice varied in area by movement of a plunger 67 which is loaded by a spring 68 adjustable by a screw 69 to provide the desired supply pressure, for example 30 p.s.i. A plunger 70 of the valve 65 is actuated by a solenoid R2 and disposed, when the solenoid is energized, in a position to admit air to the regulator 66^a and into a conduit 66 leading to the head end of the cylinder 28. Interposed in the conduit 66 is a restriction 71 adjustable by a needle which may be turned by a screw 72 to limit the flow of the air into the cylinder to a rate which is only a small fraction of the flow capacity of the conduit 66.

At the time of admission of the air through the restriction 71, the hone is collapsed and offers very little resistance to the movement of the piston 27. Thus, as the air enters, the piston starts to move causing the pressure in the cylinder to drop to a low value because of the restriction of the continuing air supply. Even at this reduced pressure, the piston continues to move and expand the hone rapidly until the working faces of the sticks 22 come into actual contact with the bore wall 11. Then, the pressure starts to build up in the cylinder and soon attains the full value, 30 p.s.i., of the supply pressure. Under this working pressure abrading of the bore wall continues at the proper rate.

When the bore attains the desired size as evidenced by closure of the switch 62, the solenoid R2 is deenergized by means to be described later and the plunger 70 is returned to the position shown in the drawing. As a result, high pressure air from the source 64 is admitted to a conduit 75 having a flexible portion 76 leading to the rod end of the cylinder 28. Under this pressure, the piston 27 and the expanding cams 24 are retracted rapidly by virtue of a by-pass 76^a around the restriction 71 including a spring loaded check valve 77 which opens automatically and permits the free flow of air out of the head end of the cylinder 28 and through the valve 65 to an escape outlet 98^a. The hone is thus collapsed rapidly without interference by virtue of the location of the restriction 71 in the conduit through which air is passed to the head end of the cylinder 28 for rapidly expanding the hone and bringing the stones into contact with the bore wall under light pressure.

By expanding the hone rapidly into full contact with the bore wall and retracting the actuating piston at high speed, it will be apparent that the duration of the honing cycle may be reduced to a minimum. At the same time, any desired working pressure may be employed as determined by the adjustment of the regulator 66. The construction of the expanding mechanism and its control are exceedingly simple thus reducing the overall cost of manufacture as compared to the structures heretofore used in production honing machines.

With a simple addition to the pneumatic expanding mechanism above described, this mechanism may be utilized to perform the additional function of automatically reconditioning the working surfaces of the stones 22 to correct for glazing or other conditions which sometimes develop in service use and interfere with the cutting efficiency of the stones. To this end, the invention contemplates increasing the working pressure automatically when a condition of reduced cutting efficiency is encountered as evidenced for example by failure of the up-to-size signal to be given within a predetermined time normally sufficient to enlarge the bore to the desired size.

Such an increase in the expanding pressure may be effected through a valve 80 normally closed by a spring 81 and opened by energization of a solenoid R3. When the valve is open, air from the high pressure source 64 is admitted to a conduit 82 leading to the conduit 66 beyond the restriction 71. In other words, the working pressure is increased from the normal value of 30 p.s.i. to the full supply pressure of 50 p.s.i. This is sufficient to break down any glaze that may have developed on the faces of the stones 22 thus restoring the cutting efficiency of the abrasive and continuing the honing action at an increased rate so as to bring the bore up to size rapidly.

Detection of the condition of reduced cutting efficiency is effected in the present instance by an electrically operating timer 84 such as is sold under the trade designation of Microflex by Eagle Signal Corporation. As is well understood in the art, such timers are activated by energization of a motor 85 whereupon, after the lapse of an interval determined by the timer setting, closes a switch 86 to complete a circuit for energizing the solenoid R3. Herein, the timer motor 85 is connected in parallel with the solenoid R2 and thus is energized and measuring of the time interval started at a time substantially coincident with the starting of the honing action. When the motor is deenergized, the timer is reset automatically and thus prepared for measuring a new time interval.

Operation

With the parts positioned as shown on the drawing and assuming that the motor 15 is running and pressure fluid is available at the different sources 18, 53 and 64, a complete honing cycle is executed automatically in response to the manual closure of a switch 89. This energizes a relay 90 whose switch 91 energizes a solenoid R1. The latter opens a valve 92 admitting pressure fluid from the source 18 to the pilot valve 43 which directs the fluid to the lower end of the plunger 93 to maintain the raised position of the plunger and thus allow the fluid to flow through the valve 19 to the rod end of the cylinder 94. Through a conduit 96, the fluid in the head end of the cylinder escapes to the return side of the pressure source 18. As the head 16 descends, the hone enters the work bore and the disk 31 turns counter-clockwise. In the initial downward movement of the head 16, a switch S1 is closed as by a cam (not shown) on the head thus completing a circuit for holding the relay 90 energized during the remainder of the cycle. After the hone has passed the full length of the bore and thus completed a stroke of the desired length, the dog 33 engages a lug 95 and shifts the arm 36 to actuate the follower 44 and close the switch S2. At the same time, the cam 37 rocks the lever 38 to reverse the pilot valve 43.

Closure of the switch S2 completes a circuit for energizing the solenoid R2 thus shifting the valve plunger 70 to admit air from the source 64 to the pressure regulator 66. As described above, the air flow through the restriction 71 and to the cylinder 28 moves the piston 27 causing the hone to be expanded rapidly until the sticks 22 come into actual contact with the bore wall 11. Thereafter, the pressure builds up to the full working

value and continues during the ensuing up stroke of the hone.

Reversal of the pilot valve 43 directs pressure fluid to the upper end of the plunger 93 thus shifting the latter downwardly thereby applying pressure to the head end of the cylinder 94 and connecting the other end to the drain line 96. The head then moves upwardly and the disk 31 clockwise until the dog 32 shifts the arm 36 reversely far enough for the cam 37 to reverse the position of the pilot valve 43 but not far enough for the follower 44 to drop off from the end of the arm. Thus, the switch S2 remains closed thereby continuing the energization of the solenoid R2 and the application of the normal working pressure behind the piston 27 of the pneumatic expander.

Such reciprocation of the expanded hone axially back and forth in the bore 11 continues until the bore has been enlarged to the desired size determined by the sizing device 50. When the up-to-size signal is given as evidenced by closure of the switch 62, a circuit for energizing the solenoid R4 is prepared but this circuit remains open until the end of the next down stroke of the hone when the cam 37 rocks the lever 38 to reverse the valve 43 and also close the switch S3. The solenoid is thus energized and through the connection 40, its armature holds the lever 38 in its actuated position against the force of the spring 98. As a result, upward movement of the hone is continued beyond the upper end of the normal working stroke and until the head 16 reaches its fully withdrawn position shown in the drawing at which the switch S1 is opened. This interrupts the holding circuit for the relay 90 thus deenergizing the solenoid R1 to close the valve 92 and stop the reciprocating actuator 17.

In the withdrawing movement of the hone the arm 36 is swung by the dog 32 far enough in the clockwise direction to pass the follower 44 thereby opening the switch S2. This deenergizes the solenoid R2 allowing the spring 97 to return the plunger 70 to the position shown in the drawing. Pressure fluid from the source 64 is thus admitted through the conduit 75 to the rod end of the cylinder 28 thus moving the piston 27 to permit retraction of the stones 22 by the springs 26. Such collapse of the hone at a rapid rate is permitted by the escape of air from the head end of the cylinder 28 through the automatic check valve 77 and to the outlet 98 through the valve 65.

The timer 84 is adjusted manually to measure an interval somewhat longer than that normally required for the bore 11 to be enlarged to the desired diameter as evidenced by closure of the switch 62. Since the timer motor 85 is connected in parallel with the solenoid R2, the time cycle will start with the expansion of the hone as a result of which a failure of the sizing switch 62 to close before the timer switch 86 is closed is evidence of inefficient action by the hone. When this condition arises, the solenoid R3 will be energized by closure of the timer switch 86 and the working pressure of the hone will be increased by the higher pressure then applied to the expanding actuators 27, 28.

Under this increased pressure, any glaze that may be present on the abrasive surface will be broken down and the cutting efficiency restored. Enlargement of the bore to the desired final sizes takes place rapidly and, as soon as the up-to-size signal is given by closure of the switch

62, the cycle is terminated as before by full withdrawal of the hone from the bore coupled with rapid collapse of the hone as above described.

A preferred arrangement of the fluid circuits is shown 5 in Fig. 2 wherein the valve 65 is mounted on the reciprocating tool head and compressed air, at the different regulated pressures above described, is delivered through a single flexible section in connection 110 between the valves 65 and 80. In this instance, the valve 80 is of the fourway type adapted when the solenoid R3 is deenergized to deliver air through a check valve 101 to the connection 110 at a normal working pressure, for example, 30 p.s.i. maintained by a regulator 102. The pressure in the connection 10 is increased to the desired 10 higher value, for example, 50 p.s.i. when the solenoid R3 is energized, this pressure value being maintained by a regulator 103 also supplied from the compressed air source 64. The air flows to the conduit 110 through a check valve 104. The check valves prevent a back pressure from being applied to either of the two regulators 102 and 103.

I claim as my invention:

1. In a machine for honing the wall of a bore, the combination of, a rotary tool having movable abrasive elements, expanding means therefor, a piston coupled to said expanding means, a cylinder enclosing and guiding said piston, a source of fluid under a predetermined pressure, means for admitting said fluid at a reduced pressure to said cylinder to expand said tool against the bore wall, a device for gaging the size of said bore and operable to interrupt the expanding pressure on said hone when the bore has been enlarged to a predetermined diameter, a timer for measuring an interval longer than that normally required for the bore to attain said predetermined diameter while said hone is under said reduced expanding pressure, and means controlled by said timer and operable upon expiration of said interval to increase the pressure of the fluid expanding said hone.

2. In a machine for honing the wall of a bore, the combination of, a rotary tool having movable abrasive elements, expanding means therefor, a piston coupled to said expanding means, a cylinder enclosing and guiding said piston, a source of fluid under a predetermined pressure, means for admitting said fluid at a reduced pressure to said cylinder to expand said tool against the bore wall, a device for gaging the size of said bore and operable to interrupt the expanding pressure on said hone when the bore has been enlarged to a predetermined diameter, a timer for measuring an interval longer than that normally required for the bore to attain said predetermined diameter while said hone is under said reduced expanding pressure, and means controlled by said timer and operable upon expiration of said interval to connect said pressure source directly to said cylinder and thereby increase the expanding pressure exerted on said abrasive elements.
